UNITED STATES PATENT OFFICE.

WALTER J. BEATTIE, OF COHOES, NEW YORK, ASSIGNOR TO THE BEATTIE MANUFACTURING CO., OF COHOES, NEW YORK, A CORPORATION OF NEW YORK.

OPERATING MECHANISM FOR FOLDING-MACHINES.

1,164,976.

Specification of Letters Patent.

Patented Dec. 21, 1915.

Application filed June 22, 1911. Serial No. 634,679.

To all whom it may concern:

Be it known that I, WALTER J. BEATTIE, a citizen of the United States, residing at Cohoes, county of Albany, and State of New York, have invented certain new and useful Improvements in Operating Mechanism for Folding-Machines, of which the following is a specification.

The invention relates to such improvements and consists of the novel construction and combination of parts hereinafter described and subsequently claimed.

Reference may be had to the accompanying drawings, and the reference characters marked thereon, which form a part of this specification. Similar characters refer to similar parts in the several figures therein.

Figure 1 of the drawings is a view partly in side elevation and partly in vertical section taken on the broken line 1—1 in Fig. 2, of a folding-machine provided with my improved operating-mechanism. Fig. 2 is a view in front elevation of the same, with the templet-support broken away. Fig. 3 is a view in rear elevation of the same. Fig. 4 is a plan view of the table and infolders of the machine. Fig. 5 is a horizontal section taken on the broken line 5—5 in Fig. 1, showing a plan view of the treadle.

The principal object of my invention is to provide operating-mechanism for the folding and pressing elements of a machine for folding cloth-blanks such as are used in the manufacture of shirts, collars and cuffs and the like, and more particularly to provide such mechanism in a form such that the successive movements of the folding and pressing elements are accomplished in the proper order by the movement of a single element by foot or other power.

Another object of the invention is to provide operating-mechanism of the character described, adapted to coöperate interchangeably with the folding and pressing elements for different styles of blank.

Referring to the drawings wherein the invention is shown in preferred form, 1, represents the frame of the machine which supports the operating-mechanism; and, 2, is a bed or table which supports the folding and pressing elements. Said table is removably mounted upon the frame by means of bolts, 3, permitting a table supporting the folding and pressing elements for one form of blank to be removed from the frame, and a table

supporting the folding and pressing elements for another form of blank to be substituted therefor at will, the operating-mechanism mounted upon the frame being adapted to coöperate interchangeably with the folding and pressing elements for different styles of blank.

The folding and pressing elements comprise a templet, 4, which may be of any known form; infolders, 5, movable inwardly and outwardly upon the bed to coöperate with the templet; and a vertically movable bed, 6, upon which the blank is placed to be folded, and which is adapted to be moved upward to press the folded edge of the blank between said bed and the infolders, 5, upward movement of the infolders being limited by a stop-bar, 7, overhanging said infolders. The infolders are guided in their inward and outward movements by pivoted links, 8, in the usual manner, and they are adapted to be moved inwardly and outwardly by means of crank-disks, 9, in fixed relation to the respective beveled gears 10.

A templet is shown mounted upon a lever, 11, pivotally mounted upon the bed or table, which lever is adapted to be automatically rocked to raise the templet, as by a counterweight 12. The lever is adapted to be operated against the force of the counterweight by means of a link, 13, screwed at its upper end into a yoke, 70, provided with a vertical slot, 14, to receive a pin, 15, on the lever with sufficient lost motion to permit of operation in the manner hereinafter described.

The beveled gears, 10, which actuate the infolders are adapted to be operated, respectively, by the beveled gear-segments, 16, on the respective rock-shafts, 17, upon which rock-shafts said gear-racks are secured in adjusted position by means of set-screws 18. The vertically movable bed, 6, is adapted to be connected with a vertically movable rod, 19, whereby said bed is at certain times forced upwardly to perform the pressing operation. The rod, 19, is shown screw-threaded into the vertically movable bed, permitting of its ready connection therewith and separation therefrom as desired. The link, 13, can be readily disconnected from the templet-carrying lever, 11, by unscrewing the link from the yoke, 70, and in like manner said link can be connected with a similar yoke on the die-carrying lever carried by a top or bed adapted for different

2 styles of blank. The racks, 16, are readily disengaged from and engaged with the beveled gears 10.

The several operating elements comprising the link, 13, gear-racks, 16, and bed-raising rod, 19, are adapted to be successively operated by the downward movement of a single element, 20, adapted to be operated by foot or other power. The element, 20, is shown in the form of a treadle whereby these operations can be accomplished successively by a single downward movement of the foot of the operator. The rear end of the treadle-lever, 20, is bifurcated, forming the two branches 21 and 22. The longer branch, 22, of the treadle-lever is connected by a link, 23, with a pawl-carrying member, 24, pivotally mounted upon the cross-shaft, 25, upon which cross-shaft is fixed a gear-wheel, 26, and a ratchet, 27, adapted to be engaged by the pawl, 28, mounted upon said pawl-carrier, 24, and the parts are so proportioned and arranged that a complete downward movement of the treadle-lever, 20, will cause a one-sixth rotation of the gear, 26, through said pawl and ratchet. The gear, 26, meshes with a pinion, 29, which is rotatively mounted in fixed relation with a gear-wheel, 30, adapted to mesh with a pinion, 31, fixed upon the cam-shaft 32. The several gears and pinions are so proportioned that a one-sixth rotation of the gear, 26, will cause a complete rotation of the pinion 31. Fixed upon the cam-shaft, 32, are two cams 33 and 34. The cam, 33, is adapted to engage a cam-follower, 35, on the end of a rocker-arm, 36, fixed upon the rock-shaft, 37, and the cam, 34, is adapted to engage a cam-follower, 38, on a lever, 39, pivotally mounted upon said rock-shaft 37.

From a comparison of Fig. 1 with Figs. 2 and 3, it will be understood that as shown in Fig. 1, cam, 34, and lever, 39, are somewhat in rear of the cam, 33, and rocker-arm 36. As the cams, 33 and 34, move in the direction of the arrow, 40, in Fig. 1, it will be seen that the initial movement of the cams causes the abrupt rise on the cam, 34, to engage the follower, 38, to quickly raise the lever, 39, thereby forcing upward the link, 13, and causing the templet, 4, to be brought quickly down upon the bed or upon a blank placed upon the bed, after which said lever, 39, is held in a raised position by a rest on said cam, 34, until the cam-follower, 35, has been engaged by the cam, 33, and raised sufficiently to cause an inward movement of the infolders over the edges of the templet sufficient to hold the templet down when released from the influence of the link 13. The cam, 33, terminates abruptly, permitting the arm, 36, to fall quickly to permit a return movement of the infolders upon the completion of the folding and pressing operations. The rocker-

arm, 36, causes operation of the toothed rack, 16, by means of an arm, 41, fixed upon the rock-shaft, 37, and connected by link, 42, with an arm, 43, on the rear rock-shaft, 17, said arm, 41, being adapted to directly engage a rocker-arm, 44, fixed upon the front rock-shaft, 17, said rocker-arm, 44, being provided with a friction-roller, 45, in the path of said arm 41. A return movement of the infolders when released is accomplished by means of a coil-spring, 46, which connects together two arms, 47 and 48, on the respective shafts 17. The rod, 19, is pivotally connected at its lower end at, 50, with a lever, 51, fulcrumed at, 52, upon the frame of the machine, and having its front end in the path of the shorter rearwardly projecting member, 21, of the treadle-lever, whereby the final power-induced movement of the treadle-lever will cause said lever, 51, to be raised and the rod, 19, to be forced upward to raise the bed, 6, to perform the pressing operation upon the folded blank. The treadle, 20, is normally held raised by the spring 53.

As a means for preventing inertia of the moving parts from carrying the gear, 26, beyond a one-sixth rotation at each operation of the treadle, I have shown the hub, 54, of said gear, 26, formed with six symmetrically disposed notches, 55, one of which is adapted to receive a spring-actuated dog, 56, upon the completion of each one-sixth rotation of the gear 26. The dog, 56, is in the form of a slide mounted in the barrel, 57, and has a pin, 58, projecting through a slot in the side of the barrel into the path of a cam-shaped member, 59, on the upper end of a rod, 60, which is connected at, 61, with the longer rearward member, 22 of the treadle-lever. The cam-shaped member, 59, plays through a guide-plate, 62, mounted upon the barrel, 57, and is adapted when the treadle is in raised position to hold the dog, 56, out of engagement with the hub, 54, of the gear-wheel, 26, but as soon as the treadle is depressed the cam-shaped member, 59, is moved upward releasing the pin, 58, and permitting the dog to be forced by its actuating spring, 63, against the face of the hub, 54, whereby it is adapted to enter the next notch, 55, which is brought opposite said dog, and having entered said notch the dog acts as a positive stop for the gear 26. As the treadle is restored to elevated position, the cam-shaped member, 59, is again brought into engagement with the pin, 58, to withdraw the dog, 56, from the notch, 55, leaving the gear, 26, free to be again partially rotated. It will thus be seen that a successive downward movement of the treadle operates successively in the proper order, first the templet, 4, to bring the same down upon the blank on the bed of the machine; secondly, to move the infolders inward to inturn the edges of

the blank over the templet in the usual manner; and thirdly, to raise the bed to press the folded blank.

I do not wish to be limited to any particular type of folding and pressing elements, as, for certain purposes of the invention these may be of any known type.

The return movement of the lever, 51, which may be termed the pressing-lever, is limited by a screw, 65, which is adjustable in a bracket, 66, in the path of the rear of said lever.

What I claim as new and desire to secure by Letters Patent is—

15. 1. In a machine of the class described, and in combination, a frame; a bed removably mounted upon said frame; folder elements mounted upon and removable with said bed; and operating-mechanism mounted 20 upon said frame, said operating-mechanism and said folder elements having directly interengaging members, which members alone comprise the operating connections between the operating-mechanism and the folder elements.

2. In a machine of the class described, and in combination, folding and pressing elements; an operating-member; a gear-wheel; pawl-and-ratchet mechanism whereby said 30 gear-wheel is operatively connected with said operating-member; operating-mechanism for the several folding elements adapted to be actuated by said gear-wheel; a lever supported in the path of final movement of 35 a portion of said operating member; and a rod connecting said lever with said pressing-mechanism.

3. In a machine of the class described, and in combination, folding and pressing elements; an operating-member; a gear-wheel; pawl-and-ratchet mechanism whereby said 40 gear-wheel is operatively connected with said operating-member; a cam-shaft; a gear-wheel fixed on said cam-shaft in operative 45 connection with said first mentioned gear-wheel; cams on said cam-shaft; cam-actuated members operatively connected with the several folding-elements; a lever supported in the path of final movement of a portion 50 of said operating-member; and a rod connecting said lever with said pressing-mechanism.

4. In a machine of the class described, and in combination, folding and pressing elements; an operating-member; a gear-wheel; pawl-and-ratchet mechanism whereby said 55 gear-wheel is operatively connected with said operating-member; a cam-shaft; a

speed-increasing train of gears between said cam-shaft and said gear-wheel; cams on said cam-shaft; cam-actuated members operatively connected with the several folding-elements; a hub for said gear-wheel provided with notches symmetrically disposed at intervals corresponding with a complete rotation of said cam-shaft; a yielding dog adapted to ride upon said hub and to automatically enter the respective notches therein; and a cam-shaped member connected with said operating-member whereby said dog is automatically withdrawn at the final return movement of the operating-member, and is automatically released at the beginning of the operating movement of said operating-member. 75

5. In a machine of the class described, and in combination, folding elements comprising a die and infolders; a vertically movable pressing-bed; a frame; a bed removably mounted upon said frame, upon which bed 80 said folding and pressing elements are mounted; folder-actuating beveled gears rotatively mounted upon said bed; a pair of rock-shafts mounted upon said frame; gear-segments fixed upon said shafts respectively 85 engageable with the respective beveled gears; a third rock-shaft; an arm fixed upon said third rock-shaft operatively connected with each of said first mentioned rock-shafts; a rocker-arm fixed upon said third 90 rock-shaft; a cam-follower lever; a lost-motion connection between said cam-follower lever and said die, whereby the die is operated; a counterweight for said die; a cam-shaft; cams on said cam-shaft engageable, 95 respectively, with said rocker-arm and said cam-follower lever; an operating-member; a gear-wheel; pawl-and-ratchet mechanism whereby said gear-wheel is operatively connected with said operating-member; a speed-increasing train of gears between said gear-wheel and said cam-shaft; means for automatically stopping the movement of said gear-wheel at each complete rotation of said cam-shaft; a pressing-lever; a rod connecting said pressing-lever with said pressing-bed; and a projection on said operating-member engageable with said pressing-lever during the final operating movement thereof. 100

In testimony whereof, I have hereunto 110 set my hand this 23rd day of May, 1911.

WALTER J. BEATTIE.
